PRESSURE LOCK ARRANGEMENT FOR LOOSE MATERIAL

Ernst Mohrs, Dornap, and Adolf Claus, Wuppertal-Barmen, Germany, assignors to Firma Rheinisch-Westfälische Kalkwerke Aktiengesellschaft, Dornap, and Firma Maschinenfabrik Adolf Claus, Wuppertal-Naechstebreck, Germany

Application December 21, 1953, Serial No. 399,314

Claims priority, application Germany December 24, 1952

20 Claims. (Cl. 214—17)

The present invention relates to a pressure lock arrangement for a loose, pulverized or granular material, and more particularly to a pressure lock arrangement in which the loose material is moved by vibrated troughs into and out of a pressure lock between two spaces of different pressure.

Known pressure lock arrangements for loose material, as are for instance used with lime and cement kilns, serve the purpose of moving material out of the kiln in which high pressure prevails, into a lower pressure space without any loss of pressure. Similarly, lock arrangements are necessary for supplying loose material into chambers in which positive or negative pressure is present. According to the known arrangements the material passes into or out of the kiln through one of two pressure locks which are gas-tightly closed by mechanically operated lock gates which are opened and closed in a predetermined order. The lock gates are operated through bevel gears, worm gears, or other transmission means. The supplied or discharged material slides along the walls of the lock chambers from one lock chamber to the other over the opening and closing lock gates. Such known arrangements have the disadvantage that frequently the lock gates do not close completely, which may occur when during the closing operation a solid body, such as a stone, jams a lock gate. Since the lock gates have to be airtightly closed, the mechanism must be designed to be strong enough to close the lock gates with great force so that the known pressure lock arrangements for loose material are very heavy and expensive to manufacture.

It is one object of the present invention to overcome the disadvantages of the known pressure lock arrangements for loose material, and to provide a pressure lock arrangement which is comparatively light, operates reliably, and requires little space in vertical direction.

It is another object of the present invention to provide a pressure lock arrangement in which loose material is vibrated to pass through a lock gate.

It is a further object of the present invention to pile loose material on a trough behind a lock gate, and to vibrate the trough to move the loose material through the opened lock gate.

It is a still further object of the present invention to provide means for operating the lock gates, and vibrator means for the trough means in a predetermined order and sequence.

With these objects in view the present invention mainly consists in a pressure lock arrangement for transferring a loose material from a container into a space having different pressure, and comprises, in combination, a lock chamber member mounted on a lower part of the container and being formed at the upper part thereof with an inlet opening communicating with the interior of the container and at the lower part thereof with an outlet opening, oscillatable delivery means within the container located in the region of the inlet opening and adapted to deliver loose material from the container into the lock chamber when oscillated and to withhold loose material

2

when at a standstill, vibrator means for oscillating the oscillatable delivery means whenever required, first operating means for closing and opening the inlet opening located at the upper part of the lock chamber member, and second operating means for closing and opening the outlet opening at the lower part of the lock chamber member.

A preferred embodiment comprises first oscillatable trough means arranged in the lower portion of the container, first vibrator means for oscillating the first trough means, a lock chamber member formed with an inlet opening in the upper part thereof communicating with the container and being located adjacent the first trough means, and also formed with an outlet opening in the lower part thereof, a first lock gate on the lock chamber member for opening and closing the inlet opening, a second lock gate on the lock chamber member for opening and closing the outlet opening, a second oscillatable trough means located within the lock chamber member underneath the inlet opening and adapted to receive loose material passing through the opened first lock gate and to hold the material while at a standstill, the second trough means having one end located adjacent the outlet opening, second vibrator means connected to the second trough means for oscillating the same so that loose material on the trough means is moved toward the outlet opening, first and second operating means for alternately opening and closing the first and second lock gates, respectively, and control means for actuating the vibrator means and the operating means in a predetermined sequence so that the first lock gate is opened and the second lock gate is closed when the first vibrator means oscillates the first trough means and so that the second lock gate is opened and the first lock gate is closed when the second vibrator means oscillates the second trough means.

In the arrangement of the present invention the loose material is poured onto a trough while the vibrator of the trough is not operating so that a conical pile is formed on the trough according to the angle of repose of the material. Since the vibrator is not operated the material does not move, and air-tight closing of the lock gates is assured since no material can get between the sealing faces of the lock gates.

All kinds of vibrators may be used in the arrangement of the present invention, for instance vibrators having a directed force, rotating vibrators, compressed air vibrators, electromagnetically operated vibrators, and mechanically operated vibrators.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a vertical sectional view through a pressure lock arrangement according to the present invention;

Fig. 2 is a cross sectional view taken on line 2—2 in Fig. 1;

Fig. 3 is a side elevation of the arrangement;

Fig. 4 is a plan view of the arrangement;

Fig. 5 is a fragmentary side view of a detail;

Fig. 6 is a fragmentary plan view of the detail shown

in Fig. 5;

Figs. 7 and 8 are side elevations of constructive elements;

Fig. 9 is a cross section on line 9—9 in Fig. 6 on an enlarged scale; and

Figs. 10a to 10g are diagrammatic views illustrating consecutive positions of the means for operating the lock

gates and the vibrator means according to the present invention.

Referring now to the drawings and more particularly to Figs. 1 and 2, a container under pressure, such as the kiln 1 has in the lower part thereof a hopper 2 provided with an opening 3. Loose material such as finished lime, falls into the hopper and passes through the opening 3 onto a slightly inclined trough means 4. The material is retained by the trough 4 in the tubular outlet 3 and in the hopper. The trough 4 is mounted on four resilient rubber members 7 and 8 in the casing 6 which is part of the container 1. The rubber members 7 are secured to the lateral walls 9 of the casing 6 on suitable supports, while the rearwardly arranged rubber members 8 are secured to the bottom plate 10 of the casing 6. A connecting means 11 is secured to the trough means 4 and passes to the outside through an opening in the wall of the casing 6. A sealing sleeve 12 air-tightly seals the casing 6 at the point where the connecting means 11 passes through the wall. A vibrator means 13 is secured to the outer end of the connecting means 11, and produces oscillations of the trough means 4, when actuated. Preferably the bottom plate 10 is detachable so that the kiln and the trough 4 are accessible when the bottom plate 10 is removed.

A lock chamber member 16 is secured to the container 1, and communicates with the container through the inlet opening 5' which is closed and opened by a first lock gate 5. The lock chamber member 16 has an outlet opening 18' which is closed by a second lock gate 18. Hinges 14 pivotally support the lock gates which provide an air-tight seal of the lock chamber 16. When the first lock gate 5 is opened and the vibrator 13 is started by means which will be described in greater detail hereinafter, the vibration of the trough means 4 effects movement of the material piled up on the trough 4 so that the material passes through the inlet opening 5' into the interior of the lock chamber member 16 and is piled up on a second trough means 17 onto which it is guided by a hopper 19. Members 7', 8', 10', 11', 12' and 14' corresponding to the members 7, 8, 10, 11, 12 and 14 of the trough means 4 are associated with the trough means 17, but only partly shown in the drawing.

When the used material has been transferred by the vibrated trough means 4 into the lock chamber member 16, the vibration of the trough means 4 is stopped, and the lock gate 5 is closed. Further material falling out of the kiln 1 is again retained in the hopper 2, and on the trough 4.

After the lock gate 5 has been closed, the lock gate 18 is opened, and thereupon the vibrator means 20 started so that the loose material piled up on the trough means 17 in the lock chamber member 16 is moved through the outlet 18', whereupon the vibrator 20 is stopped, and then the lock gate 18 closed.

After closure of the lock gate 18, the lock gate 5 is opened, the vibrator 13 started, and the loose material piled up on the trough 4 in the meantime, is moved through the inlet opening 5' into the interior of the lock chamber member 16.

The arrangement is preferably supported by a frame 21 consisting of beams. The cover sheet 22 closes the kiln 1 air-tightly. A manhole 23 is provided in the cover sheet 22. The hopper 2 is reinforced by members 24.

From the above description it will be apparent that loose material can be transferred by the oscillatable delivery means 4 through the open inlet 5' into the lock chamber 16 from where the material passes through outlet 18' into a space having a pressure different from the pressure in the container 1 when the outlet 18' is opened by suitable operating means.

According to a preferred embodiment of the present invention the lock gates 5 and 18 are operated by servo motors. The drive and control means for the arrangement are illustrated in Fig. 3. On a base plate 25 which

is mounted on supports 26, a motor 27 is mounted which drives through a drive shaft 29 a compressor 30. A pinion 31 is driven through worm gear means 28 from shaft 29 and meshes with gear means on the periphery of a rotary member 32 which is shown in Figs. 5 and 6 on an enlarged scale.

On one side of the rotary member 32 are mounted toothed segments 33 and 34. The toothed segment 33 is fixedly secured while the peripheral position of segment 34 can be adjusted. Corresponding toothed segments 35 and 36 are attached to the other side of the rotary member 32, the segment 36 being adjustable.

The control members 39 and 40 which effect closing and opening of the lock gates 5 and 18 by means which will be described in greater detail hereinafter, are connected for rotation with the pinions 37 and 38, respectively. During one rotation of the rotary member 32 the pinions 37 and 38, respectively are twice turned through an angle of 90° whereby a corresponding turning of the control members 39 and 40 is effected.

The rotary member 32 has a first set of bores 59 arranged in a circle and engaged by the pins 60 of the adjustable toothed segments 34 and 36 which are held on the rotary member by nut and bolt means 61 passing through bores 62. Consequently, the peripheral position of the adjustable toothed segments 34 and 36 can be changed for adjusting the time passing between actuation of the control members 39 and 40, which in turn effect operation of the lock gates 5 and 18.

The pinions 37 and 38 are preferably exchangeable gears, and are mounted on the shaft 39' by groove and key means 66. A manually operated crank member 65 is attached to the shaft 39' and permits manual operation of the arrangement.

In the preferred embodiment of the present invention illustrated in Figs. 1, 2 and 3, the lock gates 5 and 18 are operated by servo motors 44 and 48 which are operated by compressed air produced by the compressor 30. The control valve 39 is arranged in the conduit means 40 connecting the compressor with the servo motor means 44, and the control valve 40 is arranged in the conduit means connecting the compressor with the servo motor means 48. Servo motor means 44 and 48 comprise servo motors arranged on both sides of the associated lock gates. The compressed air passes through the conduit 41 to the control valves 39 and 40. The control valve 39 controls the conduits 42 and 43 for moving the servo piston of the servo motor 44 in opposite directions. The control valve 40 controls the conduits 46 and 47 for moving the piston of the servo motor 48 in opposite directions, the air being discharged through the conduit 49. The pistons of the servo motors 44 and 48 operate the connecting rods 51 and 51' which are guided in guiding means 52 and 52'. Members 53, 53' connect the rods 51, 51' with arms 54, 54' which are pivoted to the lock gates 5 and 18, respectively. By shifting of the member 53 on the rod 51 the pressure effecting closing of the respective lock gates can be adjusted. The packing member 56 seals the connecting rod 51, and prevents passing of air out of the lock chamber 16.

Preferably the return conduits 45 and 49 are so arranged that the air passing out of the same blows against the associated connecting rods 51, 51' for removing dust. A safety valve or an air reservoir may be connected with the conduit 41. The compressor 30 may be replaced by another source of compressed air.

Instead of the compressor 30, a pump may be provided which circulates an operating liquid for actuating the servo motor means 44 and 48. In this event the return conduit 45 and 49 have to be connected to an oil container to provide a closed circulation.

In order to obtain the desired sequence in the operation of the vibrators 13 and 20 with the operating means for the lock gates, cam means 57 and 63 are secured to the shaft 39' and 40', see Figs. 5 and 6. During rota-

tion of the control valves 39 and 40 the cams 57 and 63 operate actuating means 58 and 64 for the vibrators 13 and 20. Preferably the vibrators are operated by electromagnet means, not shown, and in this event the members 58 and 64 operate switches for starting and stopping the associated vibrator means 13 and 20.

The pressure lock arrangement according to the present invention operates in the following manner:

In the position shown in Fig. 10a the control valves 39 and 40 are in positions in which both lock gates 5 and 18 are closed. The rotating member 32 effects in the position of Fig. 10b turning of the control valve 39 into a position resulting in opening of the lock gate 5. In the position of Fig. 10c the cam means 57 effects operation of the actuating means 58 so that the vibrating means 13 are started and move loose material through the open lock gate 5 into the lock chamber 16 where it is received by the trough 17 and piles up on the same. Further rotation of the rotating member 32 effects closing of lock gates 5 as shown in Fig. 10d, whereupon the toothed segment 35 turns the control valve 38 and effects opening of the lock gate 18, Fig. 10e. Thereupon the cam 63 actuates the actuating means 64 of the vibrator means 20, Fig. 10f, so that the trough 17 is oscillated and moves the material piled up thereon through the open outlet 18'. Further rotation of the member 32 effects closing of the lock gate 18 whereupon the sequence of operation is repeated.

As described above, the toothed segment 34 and 36 can be mounted on the rotary member 32 in a plurality of positions which are peripherally displaced with respect to the fixed toothed segments 33 and 35. A change of the position of the adjustable toothed segments 34 and 35 does not influence the sequence of operation of the servo motors 44 and 48, but influences the operating times. The intervals between the positions 10d and 10e, and between the positions 10a and 10b are extended for the same time as the oscillating time of the vibrator means is shortened. Since the rotary member 32 is divided in 24 sectors, the operating time for each operation is one-twenty-fourth of the time required for one revolution of the member 32, assuming that the toothed segments 33—36 have a length corresponding to a quarter of the periphery of the pinions 37 and 38 and turn the same through 90°.

It will be understood that each of the elements described above, or two or more together, may also find a useful application in other types of pressure lock arrangements differing from the types described above.

While the invention has been illustrated and described as embodied in a pressure lock arrangement in which loose material piled on troughs is moved through lock gates by vibration of the troughs, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range equivalence of the following claims.

What is claimed as new and desired to be secured by Letters Patent is:

1. Pressure lock arrangement for transferring loose material from a container into a space having a pressure different from the pressure within said container, comprising, in combination, a lock chamber member mounted on a lower part of said container and being formed at the upper part thereof with an inlet opening communicating with the interior of said container and at the lower part thereof with an outlet opening; oscillatable delivery means

within said container located in the region of said inlet opening and adapted to deliver loose material from said container into said lock chamber when oscillated and to withhold loose material when at a standstill; vibrator means for oscillating said oscillatable delivery means whenever required; first operating means for closing and opening said inlet opening located at the upper part of said lock chamber member; and second operating means for closing and opening said outlet opening at the lower part of said lock chamber member.

2. Pressure lock arrangement for transferring loose material from a container into a space having a pressure different from the pressure within said container, comprising, in combination, a lock chamber member mounted on a lower part of said container and being formed at the upper part thereof with an inlet opening communicating with the interior of said container and at the lower part thereof within an outlet opening; oscillatable delivery means within said container located in the region of said inlet opening and adapted to deliver loose material from said container into said lock chamber when oscillated and to withhold loose material when at a standstill; vibrator means for oscillating said oscillatable delivery means whenever required; first operating means for closing and opening said inlet opening located at the upper part of said lock chamber member; second operating means for closing and opening said outlet opening at the lower part of said lock chamber member; and control means for operating said first and second operating means, and said vibrator means in a predetermined sequence.

3. Pressure lock arrangement for transferring loose material from a container into a space having a pressure different from the pressure within said container, comprising, in combination, a lock chamber member mounted on a lower part of said container and being formed at the upper part thereof with an inlet opening communicating with the interior of said container and at the lower part thereof with an outlet opening; oscillatable delivery means within said container located in the region of said inlet opening and adapted to deliver loose material from said container into said lock chamber when oscillated and to withhold loose material when at a standstill; vibrator means for oscillating said oscillatable delivery means whenever required; first operating means for closing and opening said inlet opening located at the upper part of said lock chamber member; second operating means for closing and opening said outlet opening at the lower part of said lock chamber member; drive means; a rotary member driven by said drive means; at least two spaced toothed segments on the periphery of said rotary member; a first turnable control member for operating said first operating means; a second turnable control member for operating said second operating means; a first pinion connected to said first control member for turning therewith; a second pinion connected to said second control member for turning therewith; said first and second pinions being engaged and turned by said toothed segments during rotation of said rotary member for alternately turning said control members; a cam means connected for rotation to said first control member; and an actuating means for starting and stopping said vibrator means projecting into the path of said cam means, said cam means effecting start of said vibrator means when said first control member effects opening of said inlet opening.

4. Pressure lock arrangement for transferring loose material from a container into a space having a pressure different from the pressure within said container, comprising, in combination, a lock chamber member mounted on a lower part of said container and being formed at the upper part thereof with an inlet opening communicating with the interior of said container and at the lower part thereof with an outlet opening; oscillatable delivery means within said container located in the region of said inlet opening and adapted to deliver loose material from said container into said lock chamber when oscillated and

to withhold loose material when at a standstill; vibrator means for oscillating said oscillatable delivery means whenever required; first fluid operated servo motor means for closing and opening said inlet opening located at the upper part of said lock chamber member; second fluid operated servo motor means for closing and opening said outlet opening at the lower part of said lock chamber member; drive means; a rotary member driven by said drive means; at least two spaced toothed segments on the periphery of said rotary member; a source of operating pressure fluid; conduit means connecting said source of pressure fluid with said first and second servo motor means; a first turnable control valve in said conduit means for operating said first servo motor means; a second turnable control valve for operating said second servo motor means; a first pinion connected to said first control valve for turning therewith; a second pinion connected to said second control valve for turning therewith, said first and second pinions being engaged and turned by said toothed segments during rotation of said rotary member for alternately turning said control valves; a cam means connected for rotation to said first control valve; and an actuating means for starting and stopping said vibrator means projecting into the path of said cam means, said cam means effecting start of said vibrator means when said first control valve effects opening of said inlet opening.

5. A pressure lock arrangement for transferring a loose material between spaces having different pressures, comprising, in combination, a lock chamber member formed with an inlet opening in the upper part thereof, and with an outlet opening in the lower part thereof; a first lock gate on said lock chamber member for opening and closing said inlet opening; a second lock gate on said lock chamber member for opening and closing said outlet opening; an oscillatable trough means located within said lock chamber member underneath said inlet opening and adapted to receive loose material passing through the opened first lock gate and to hold the material while at a standstill, said trough means having one end located adjacent said outlet opening; vibrator means connected to said trough means for oscillating the same so that loose material on said trough means is moved toward said outlet opening; first and second operating means for alternately opening and closing said first and second lock gates, respectively; and control means for actuating said vibrator means and said operating means in a predetermined sequence so that said first lock gate is closed and said second lock gate is opened when said vibrator means oscillates said trough means.

6. A pressure lock arrangement for transferring a loose material between spaces having different pressures, comprising, in combination, a lock chamber member formed with an inlet opening in the upper part thereof, and with an outlet opening in the lower part thereof; a first lock gate on said lock chamber member for opening and closing said inlet opening; a second lock gate on said lock chamber member for opening and closing said outlet opening; an oscillatable trough means located within said lock chamber member underneath said inlet opening and adapted to receive loose material passing through the opened first lock gate and to hold the material while at a standstill, said trough means having one end located adjacent said outlet opening; vibrator means connected to said trough means for oscillating the same so that loose material on said trough means is moved toward said outlet opening; first and second operating means for alternately opening and closing said first and second lock gates, respectively.

7. A pressure lock arrangement for transferring a loose material from a container into a space having a pressure different from the pressure within said container, comprising, in combination, first oscillatable trough means arranged in the lower portion of said container; first vibrator means for oscillating said first trough means;

5 a lock chamber member formed with an inlet opening in the upper part thereof communicating with said container and being located adjacent said first trough means, and also formed with an outlet opening in the lower part thereof; a first lock gate on said lock chamber member for opening and closing said inlet opening; a second lock gate on said lock chamber member for opening and closing said outlet opening; a second oscillatable trough means located within said lock chamber member underneath said inlet opening and adapted to receive loose material passing through the opened first lock gate and to hold the material while at a standstill, said second trough means having one end located adjacent said outlet opening; second vibrator means connected to said second trough means for oscillating the same so that loose material on said trough means is moved toward said outlet opening; first and second operating means for alternately opening and closing said first and second lock gates, respectively; and control means for actuating said vibrator means and said operating means in a predetermined sequence so that said first lock gate is opened and said second lock gate is closed when said first vibrator means oscillates said first trough means and so that said second lock gate is opened and said first lock gate is closed when said second vibrator means oscillates said second trough means.

8. A pressure lock arrangement as claimed in claim 7 wherein said vibrator means are located outside of said container and of said lock chamber member; and including a connecting means connecting, respectively, said first and second vibrator means with said first and second trough means, and passing through the walls of said container and of said lock chamber member; and sealing means for airtightly sealing said connecting means and said container and lock chamber member.

9. A pressure lock arrangement for transferring a loose material from a container into a space having a pressure different from the pressure within said container, comprising, in combination, first oscillatable trough means arranged in the lower portion of said container; first vibrator means for oscillating said first trough means; a lock chamber member formed with an inlet opening in the upper part thereof communicating with said container and being located adjacent said first trough means, and also formed with an outlet opening in the lower part thereof; a first lock gate on said lock chamber member for opening and closing said inlet opening; a second lock gate on said lock chamber member for opening and closing said outlet opening; a second oscillatable trough means located within said lock chamber member underneath said inlet opening and adapted to receive loose material passing through the opened first lock gate and to hold the material while at a standstill, said second trough means having one end located adjacent said outlet opening; second vibrator means connected to said second trough means for oscillating the same so that loose material on said trough means is moved toward said outlet opening; first and second operating means for alternately opening and closing said first and second lock gates, respectively; drive means; a rotary member driven by said drive means; at least two spaced toothed segments on the periphery of said rotary member; a first turnable control member for operating said first operating means; a second turnable control member for operating said second operating means; a first pinion connected to said first control member for turning therewith; a second pinion connected to said second control member for turning therewith, said first and second pinions being engaged and turned by said toothed segments during rotation of said rotary member for alternately turning said control members; two cam means connected for rotation to said first control member and to said second control member, respectively; first and second actuating means for starting and stopping said first and second vibrator means, each actuating means projecting into the path of one of said

cam means, said cam means effecting start of the associated vibrator means when the lock gate associated with the respective vibrator means is opened by the control member associated therewith.

10. A pressure lock arrangement as claimed in claim 9 wherein said vibrator means are electromagnetically operated and wherein said actuating means are switches.

11. A pressure lock arrangement as claimed in claim 9 and including two other spaced toothed segments on the periphery of said rotary member for operating each of said control members twice during each rotation of said rotary member.

12. A pressure lock arrangement as claimed in claim 11 wherein said two other spaced toothed segments are detachably mounted on said rotary member for adjusting the peripheral position thereof.

13. A pressure lock arrangement for transferring a loose material from a container into a space having a pressure different from the pressure within said container, comprising, in combination, first oscillatable trough means arranged in the lower portion of said container; first vibrator means for oscillating said first trough means; a lock chamber member formed with an inlet opening in the upper part thereof communicating with said container and being located adjacent said first trough means, and also formed with an outlet opening in the lower part thereof; a first lock gate on said lock chamber member for opening and closing said inlet opening; a second lock gate on said lock chamber member for opening and closing said outlet opening; a second oscillatable trough means located within said lock chamber member underneath said inlet opening and adapted to receive loose material passing through the opened first lock gate and to hold the material while at a standstill, said second trough means having one end located adjacent said outlet opening; second vibrator means connected to said second trough means for oscillating the same so that loose material on said trough means is moved toward said outlet opening; first and second servomotor means for alternately opening and closing said first and second lock gates, respectively; a source of operating fluid; conduit means connecting said source of fluid with said first and second servomotor means; drive means; a rotary member driven by said drive means; at least two spaced toothed segments on the periphery of said rotary member; a first turnable control valve and a second turnable control valve located in said conduit for operating, respectively, said

5

10

first and second servomotor means; first and second pinions connected respectively to said first and second control valves for turning therewith, said pinions being engaged and turned by said segments during rotation of said rotary member for alternately turning said control member; two cam means connected for rotation to said first and second control valves, respectively; first and second actuating means for starting and stopping said first and second vibrator means, each actuating means projecting into the path of one of said cam means, said cam means effecting start of the associated vibrator means when the lock gate associated with the respective vibrator means is opened by the control member associated therewith.

15. A pressure lock arrangement as claimed in claim 13 wherein said source of operating pressure fluid is a compressor driven by said drive means.

16. A pressure lock arrangement as claimed in claim 14 wherein said conduit has outlet openings for air supplied by said compressor, said outlet opening being arranged opposite said servomotor means and for directing a cleaning air stream toward the same.

17. A pressure lock arrangement as claimed in claim 13 wherein said source of operating fluid is a pump driven by said drive means and circulating an operating liquid in said conduit means.

20. A pressure lock arrangement as claimed in claim 13 wherein said source of operating fluid is a compressor; a drive shaft connecting said drive means with said compressor; a pinion on said drive shaft; gear means fixed on said rotary member and meshing with said pinion so that said rotary member is driven from said drive means.

25. A pressure lock arrangement as claimed in claim 13 and including manually operated means connected to said rotary member for rotating the same.

30. A pressure lock arrangement as set forth in claim 7 and including manually operated means connected to said control means for operating the same.

35. A pressure lock arrangement as set forth in claim 9 and including manually operated means connected to one control member of said first and second control members for turning the respective control member.
